ABSTRACT: A lady's bag includes a pair of outer side members foldably connected to each other in spaced relation and having inner surfaces. The side members are movable to and from positions in which their inner surfaces are in spaced confronting relation and define a space within the bag and are releasably secured in such positions. One or more receptacles are affixed to the bag in the space.

FIG. 1

FIG. 2

INVENTOR.
MURRAY WOLF

BY

Frank Cate

ATTORNEY

LADY'S HAND OR SHOULDER BAG

DESCRIPTION OF THE INVENTION

The present invention relates to a lady's hand or shoulder bag.

The principal object of the present invention is to provide a new and improved lady's hand or shoulder bag.

An object of the present invention is to provide a lady's hand or shoulder bag of considerable holding capacity.

An object of the present invention is to provide a lady's hand or shoulder bag of great strength.

An object of the present invention is to provide a lady's hand or shoulder bag of novel appearance and simple structure.

An object of the present invention is to provide a lady's hand or shoulder bag which is inexpensive to manufacture, of simple structure, but sturdy and of considerable capacity.

In accordance with the present invention, a lady's hand or shoulder bag comprises a pair of outer side members. Connecting means foldably connects the side members to each other in spaced relation. The side members have inner surfaces and are movable to and from positions in which the surfaces are in spaced confronting relation and define a space within the bag. A receptacle is disposed in the space within the bag. Securing means releasably secures the side members in their positions.

The receptacle comprises separate individual compartments each having an opening for access to the interior of the compartment when the securing means is released. The receptacle is heat sealed and thereby secured in the space.

The connecting means comprises a strip of heat sealed material to the interior surfaces of the side members. The connecting means may comprise a connecting strip integral with the side members. The connecting means is heat sealed to the receptacle.

In order that the present invention may be readily carried into effect, it will now be described with reference to the accompanying drawing, wherein:

FIG. 1 is a perspective view of an embodiment of the lady's hand or shoulder bag of the present invention in open condition;

FIG. 2 is a side view of the lady's hand or shoulder bag of FIG. 1 in closed condition; and

FIG. 3 is a bottom view of the outer side members of the lady's hand or shoulder bag of FIGS. 1 and 2.

In the FIGS. the same components are indicated by the same reference numerals.

In FIGS. 1, 2 and 3, a pair of outer side members and 1 and 2 are foldably connected to each other in spaced relation by a connecting strip 3 (FIGS. 1 and 2). In FIG. 3, the outer side members 1 and 2 are integrally formed with the connecting strip 3, whereas in FIGS. 1 and 2 the connecting strip 3 comprises a strip of heat sealed material which is heat sealed to the inner surfaces of said members. This is partly shown by the heat seam 4 in FIG. 1.

The outer side members 1 and 2 are movable to an and from positions in which the inner surfaces thereof are in spaced confronting relation, as shown in FIG. 2, and define a space 5 within the bag (FIG. 2). FIG. 2 shows the outer side members 1 and 2 in closed condition, in which they define the space 5 within the bag. In FIG. 1, the outer side members 1 and 2 in closed condition, in which they define the space 5 within the bag. In FIG. 1, the outer side members 1 and 2 are shown in open condition in which they are substantially coplanarly disposed, so that they do not define a space within the bag, but, instead, permit completely free access to the bag.

A receptacle 6 is disposed in the space 5 within the bag, as shown in FIGS. 1 and 2. The receptacle is heat sealed to the corresponding strip 3 and is thereby secured in the space 5 within the bag. The receptacle 6 may comprise one or more separate individual compartments such as, for example, compartments 7 and 8. Each compartment has an opening for access to the interior thereof when the outer side members 1 and

2 are in open condition. The compartment 7 thus has an opening controlled by a snap catch 90 and the compartment 8 has an opening controlled by a zipper 11.

5 The outer side members 1 and 2 are releasably secured in a closed condition, in which they define the space 5 within the bag, by a securing device. The securing device comprises a securing flap 12, as shown in FIGS. 1 and 2, which is secured in the area of one end thereof to one of the side members such as, for example, the side member 1. The securing flap 12 may thus be affixed to the outer side member 1 by any suitable means such as, for example, one or more rivets or suitable fasteners 13 (FIG. 2).

10 The securing flap 12 may be permanently affixed to the outer side member 2, rather than to the outer side member 1, of course. In the area of its other end, the securing flap 12 has a suitable releasable clamping device which cooperates with a corresponding releasable clamping device affixed to the outer side member 2. Any suitable releasable clamping device may be utilized to permit the other end of the securing flap 12 to be releasably secured to the outer side member 2. The releasable securing device may, of course, be affixed to the outer side member 1, rather than to the outer side member 2.

15 In the illustrated embodiment of the present invention, the 25 releasable securing device is illustrated as a snap fastener of known type. The snap fastener comprises a hollow portion 14 affixed to the outer surface of the outer side member 2 (FIG. 2) and a projecting portion 15 affixed to the inner surface of the securing flap 12 (FIGS. 1 and 2). The portion 15 is adapted to fit into the portion 14 in known manner and to remain seated therein until pressure is exerted to separate said portions from each other. When the bag is closed, and the securing flap 12 is operative to keep the bag closed, said securing flap overlaps the receptacle 6 in a manner whereby 30 all of the compartments of said receptacle are covered by said securing flap.

20 A hand loop 16, as shown in FIG. 1, may be affixed to any suitable portion of the receptacle 6 such as, for example, to the compartment 7 of said receptacle. The loop 6 may be affixed to the bag in any suitable manner such as, for example, by a ring or by any suitable fastening means. The hand loop 16 may be replaced by any suitable shoulder or other type of loop to enable the bag to be carried or supported in any desired manner.

25 The bag of the present invention may comprise any suitable material. The connecting strip 3 preferably comprises a plastic material.

30 While the invention has been described by means of a specific example and in a specific embodiment, I do not wish to be limited thereto, for obvious modifications will occur to those skilled in the art without departing from the spirit and scope of the invention.

I claim:

35 1. A lady's hand or shoulder bag, comprising a pair of outer side members having bottom edges, a bottom member foldably connecting said bottom edges of said side members to each other in spaced relation, said side members having inner surfaces and being movable to and from positions in which said surfaces are in spaced confronting relation and define a space within the bag, a receptacle disposed in said space within the bag and having its bottom edge in unitary relation with said bottom member, and means for releasably securing said side members in said positions.

40 2. A lady's hand or shoulder bag according to claim 1, further characterized in that said receptacle comprises separate individual compartments each having an opening for access to the interior of the compartment when said securing means is released.

45 3. A lady's hand or shoulder bag according to claim 2, further characterized in that such securing means is secured to one of said side members and is releasably secured to the other of said side members and has a portion overlapping said receptacle.

4. A lady's hand or shoulder bag according to claim 1, further characterized in that said receptacle is heat sealed to said side members and thereby secured in said space.

5. A lady's hand or shoulder bag according to claim 1, further characterized in that said connecting means comprises a strip of heat sealable material heat sealed to the inner surfaces of said side members.

6. A lady's hand or shoulder bag according to a claim 1, further characterized in that said bottom member comprises a connecting strip integral with said side members.

7. A lady's hand or shoulder bag according to claim 1, further characterized in that said connecting means comprises a connecting strip integral with said side members and heat sealed to said receptacle.

8. A lady's hand or shoulder bag according to claim 1, further characterized in that said securing means is secured to one of said side members and is releasably secured to the other of said side members and has a portion overlapping said

receptacle.

9. A lady's hand or shoulder bag according to claim 1, further characterized in that said securing means is secured to one of said side members and is releasably secured to the other of said side members and has a portion overlapping said receptacle.

10. A lady's hand or shoulder bag, comprising a pair of outer side members, means foldably connecting said side members to each other in spaced relation, said side members having inner surfaces and being movable to and from positions in which said surfaces are in spaced confronting relation and define a space within the bag, a receptacle disposed in said space within the bag, and means for releasably securing said side members in said positions, said connecting means comprises a strip of heat sealable material heat sealed to the inner surfaces of said side members and to said receptacle.
